UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

RESISTANCE CONTROL APPARATUS.

Application filed June 4, 1923. Serial No. 643,328.

This invention relates to resistance control apparatus, and while not limited thereto is particularly applicable to apparatus for voltage control of audion valves and the like.

As is well known, the design and construction of such valves has been and at present is in a state of rapid development and improvement, such changes frequently involving corresponding changes in the character and values of the energy supplied to the valves and in the range of variation of such values required in service. As a result of the foregoing, certain highly meritorious types and constructions of control devices for such valves and also large quantities of existing apparatus are in danger of obsolescence unless correspondingly developed, modified, and improved.

An object of the present invention is that of adapting such potentially obsolete designs and apparatus to present and prospective needs.

Another object is that of so prolonging and extending the utility of such designs and such apparatus without substantial intrinsic modification thereof and with a minimum of addition thereto.

Another object is that of co-ordinating and amplifying such existing types of apparatus to adapt the same to present and prospective needs and also reducing the number of elements and space requirements and concentrating and simplifying the control thereof.

Other objects and advantages will hereinafter appear.

In the accompanying drawing wherein are illustrated certain preferred embodiments of the invention,

Figure 1 is a side elevational view of such an embodiment;

Fig. 2 is a rear elevational view of one of the portions thereof; while,

Fig. 3 is a perspective view of a slightly modified construction.

Referring to the drawing and particularly to Figs. 1 and 2 thereof, the same illustrate associated, individually operable resistance control devices having supporting elements in common and comprising a plurality of U-shaped frame members 5 and 6, preferably composed of metal, to be secured to a common connecting member 7, preferably conductive and of channeled formation as

shown, by bolts or screws 8 and 9 and to be permanently secured upon an insulating base or panel 10. Frame members 5 and 6 are adapted to support the variable resistance devices 11 and 12 each having suitable terminals and operating means therefor, the latter preferably including concentric shafts 13 and 14 penetrating the control panel 10 and provided on the opposite side thereof with individual operating means such as knobs 15 and 16. Indicators such as 17 may be fixed to one or both of said shafts for indicating the setting of the individual elements operable thereby.

Obviously the longitudinal flanges of the connector 7 are adapted to coact directly with the adjacent edge portions of frame members 5 and 6 for maintaining a coplanar relation of the operating shafts 13 and 14 whereas said connector is otherwise so shaped, as shown, to provide not only for actual parallelism of said shafts but further to provide and maintain a concentric or telescopic relation thereof, thus again providing for longitudinal adjustment of said shafts and preventing operative interference thereof.

The resistance devices 11 and 12 comprise generally, resistor coils 18 and 19 mounted respectively upon rotatable members 20 and 21, the rotatable members 20 including a circumferentially grooved annular insulating member to receive and hold the resistor coil 18 in spaced relation with respect to the metallic end caps of the member 20; whereas the rotatable member 21, comprises a pair of insulating disks having upon their adjacent faces and adjacent the respective peripheries thereof inwardly facing annular grooves to receive the resistor element 19 the latter comprising a relatively large number of turns of fine resistance wire wound upon a flexible strip of fibre or other suitable insulating material. Each of said coils has a terminal portion thereof in electrical connection with a conductive portion of its associated rotatable member, said rotatable members being in electrical contact with the respective frame members 5 and 6, said frames being in turn electrically connected by means of the connecting member 7. Further the arrangement may preferably be such as to provide for potentiometer connection or for simple rheostat connection of either or both of the resistance devices.

Details of said resistance devices are disclosed and claimed in my copending applications, S. N. 561,136, filed May 15, 1922, and S. N. 622,078 filed March 1, 1923, and hence further description herein of these elements per se is deemed unnecessary.

In practice the rotatable members 20 and 21 are preferably secured upon concentric shafts 13 and 14, respectively, in the usual manner, whereas the element 11 is also secured to the concentric shaft 22 and such securing of said element may be conveniently effected by means of the usual set screw 23 acting through and upon hub portion 24 and also penetrating a suitable opening in tubular shaft 22 and producing a clamping action on said shaft 13.

An auxiliary resistance element 25 of suitable or desired ohmic value is secured to the resistance device to be in circuit therewith. In practice said resistance element 25 may preferably comprise a coil 26 of a relatively large number of turns of resistance wire 27, said wire being preferably wound upon a flexible strip 28 of fibre or other suitable insulating material and terminally anchored thereto, one end of said resistance wire being so anchored preferably by means of a metal grommet 29 said grommet serving as a mounting means for one end of the resistance element while the opposite end is provided with an aperture 30. In mounting said resistance element 25, as shown in Fig. 1, the end having the grommet 29 therein is secured to and upon the terminal device 31 and said strip 28 having the resistance element 25 coiled thereon is thereafter bent or bowed to bring the aperture 30 into register with bolt 8 and is thereafter secured by nut 32.

In Fig. 2 is shown a modified form of mounting means for one end of the auxiliary resistance element 25, the same comprising a plate member 33 provided with a screw threaded opening 34 for the reception of screw 35 and having a projection 36 loosely connecting plate member 33 to flexible strip 28 thereby providing limited movement of said plate member 33, the same acting as a nut for mounting the end of the resistor element 25 to frame member 5 as before described. This method facilitates mounting of the auxiliary resistance element, it being readily seen that such operation may be accomplished wholly from without the frame, without involving disassembly of any part of the device.

The value of the resistance of the element 25 to be included in circuit may be varied by means of a slider 37 having one lead of the controlled circuit connected thereto. Said slider in practice may preferably comprise a metal strip formed as best shown in Fig. 3, having portions 38 bent as shown not only to support the same but also to

make contact with the resistance 27. A clamping screw 39 is provided in the outstruck portion 40, said screw 39 being provided with a nut 41 for locking the slider in the desired position and also with a terminal device 42. The resistance element is to be in circuit with element 11 and such joint circuit may be traced from the terminal device of slider 37, through that portion of the resistance 26 determined by the positioning of said slider to terminal device 31 by contact finger 43 to and through resistance 18 or through the portion thereof determined by the rheostat setting and thence to frame 5 and its associated terminal.

Referring now to Fig. 3, the same illustrates a pair of main resistance varying elements similar to the element 11, arranged, connected and supported for independent operation in the manner aforescribed.

One or both of said main resistance elements is in this instance provided with an auxiliary resistance element 25* which is functionally similar to the corresponding element 25 aforescribed but which is modified in matters of structure, dimensions, etc., better to adapt the same to certain special requirements and conditions.

In this arrangement the rheostat terminal device 44 alone is adapted to provide both for mechanical support and electrical connection of the element 25*, whereby the angular position of said element with reference to the rheostat frame may be varied at will to suit the conditions of any particular installation.

It is of course to be understood that the auxiliary resistance elements 25 and 25* may be substituted one for the other and that either may be replaced by a mechanically similar unit having a different ohmic or other electrical value whenever necessary or desirable in order to adapt the device, either electrically or mechanically to a particular installation. Also it is to be observed that in accordance with the present teaching practically any desired number of independently operable resistance or potential controlling devices or both may be arranged for joint electrical connection and mechanical support.

Again, optionally as shown in Fig. 3, shaft 13 may be constructed of insulating material as indicated at 18* and frame 5 may be insulated from connector 7* as by an insulating bushing 45, whereby the individual resistance varying devices may be adapted to control electrically independent circuits. Thus if desired all the resistance and potential control instrumentalities of a complete installation may be arranged within approximately the same mounting area ordinarily occupied by a single instrumentality.

What I claim as new and desire to secure by Letters Patent is:—

1. In resistance control apparatus, the combination with a self supporting rheostat to be secured to a base, of an attachment for substantially augmenting the total ohmic value of said rheostat, comprising an auxiliary flexible resistor device and terminal means providing for arcuate positioning of the latter about said rheostat and in circuit with the resistor element thereof.
2. In resistance control apparatus, the combination with a rheostat having associated supporting means, of an attachment for substantially augmenting the total ohmic value of said rheostat, comprising an auxiliary flexible resistor device having terminal means including a rigidly secured terminal device having parts to cooperate directly with said rheostat supporting means to provide for arcuate positioning of said auxiliary resistor about said rheostat and for terminal connection thereof in circuit with said rheostat.
3. In resistance control apparatus, the combination with a rheostat having associated supporting means, of an attachment for substantially augmenting the total ohmic value of said rheostat, comprising an auxiliary flexible resistor device having terminal means including a rigidly secured terminal device having parts to cooperate directly with said rheostat supporting means to provide for arcuate positioning of said auxiliary resistor about said rheostat and for terminal connection thereof in circuit with said rheostat, said auxiliary resistor having means for preselecting the effective ohmic value thereof.
4. In resistance control apparatus, the combination with a rheostat having associated supporting means, of an attachment for substantially augmenting the total ohmic value of said rheostat, comprising an auxiliary flexible resistor device having terminal means including an adjustably fixed slider and a terminal device rigidly secured thereto for mechanical support and arcuate positioning of said auxiliary resistor about and in circuit with said rheostat.
5. In resistance control apparatus, the combination with a rheostat having associated supporting means, of an attachment for substantially augmenting the total ohmic value of said rheostat, comprising an auxiliary flexible resistor device having terminal means including an adjustably fixed clamping slider and a rigidly secured terminal device for mechanical support and securing of said auxiliary resistor to and in circuit with said rheostat, in a relation providing for angular adjustment of the position of said auxiliary resistor with respect to the associated supporting means of said rheostat.
6. In resistance control apparatus, the combination with a plurality of resistance varying devices having individual operating means and individual conductive supporting frames to be included in the controlled circuit, said frames having similarly disposed openings, of an elongated connector to be terminally secured to said frames adjacent to and in association with said openings for rigidly uniting and electrically connecting said devices, certain of the latter having means for securing the same upon a base to thereby provide for common support of all the devices so united thereto.
7. In resistance control apparatus, the combination with a plurality of resistance varying devices having individual operating means and individual conductive supporting frames to be included in the controlled circuit, said frames having similarly disposed openings, of an elongated conductive connector and means to co-operate with said openings for rigidly uniting and electrically connecting said devices with said connector, certain of said devices having means for securing the same upon a base to thereby provide for common support of all the devices so united, said operating means being arranged and correlated to provide for close juxtaposition of the individual operating members while maintaining independence of action thereof.
8. In resistance control apparatus, the combination with a plurality of resistance varying devices having independent supporting frames and individual operating means, of a rigid bar and means for securing said frames thereto for mechanically uniting said devices in a relation providing for close juxtaposition of certain of their respective operating elements, said bar having its longitudinal edges shaped to co-operate with adjacent portions of the respective frames for maintaining parallelism of said juxtaposed operating elements to thereby minimize operative interference therebetween.
9. In resistance control apparatus, the combination with a plurality of resistance varying devices having independent supporting frames and individual operating means, of a rigid metallic bar and means for securing said frames thereto for electrically connecting and mechanically uniting said devices in a relation providing for close juxtaposition of certain of their respective operating elements, said bar being shaped to co-operate with adjacent portions of said individual frames for maintaining a relation of said juxtaposed operating elements wherein operative interference therebetween is minimized.
10. In resistance control apparatus, the combination with a plurality of resistance varying devices having independent conductive supports, of means to coact with said supports for mechanically uniting and electrically connecting said devices.

trically connecting the latter, said means having parts to coact directly with portions of said supports for maintaining accurate relative positioning of said devices, certain 5 of said supports having means to provide for mounting upon a common base of all the devices so united.

11. In resistance control apparatus, the combination with a plurality of resistance 10 varying devices having independent supports, of means to coact with the supports of said devices for mechanically uniting and electrically connecting the latter, each of said supports having a portion extending in 15 parallel relation to a given axis of its associated resistance control device, said means comprising parts to coact with said parallel extending portions of said supports for maintaining a coplanar arrangement of said 20 axes, certain of said supports having means to provide for mounting upon a common base of all the devices so united.

12. In resistance control apparatus, the combination with a plurality of resistance 25 varying devices having independent supports, of means to coact with the supports of said devices for mechanically uniting and electrically connecting the latter, each of said supports having edge portions extending in parallel relation to a given axis of its 30 associated resistance control device, said means comprising parallel edge portions to coact with the aforementioned edge portions of said supports for maintaining coplanar relation of said axes and said means being so formed as to maintain said axes within a common plane angularly related to said former plane, certain of said supports having means to provide for mounting upon a 35 common base of all the devices so united.

13. In resistance control apparatus, the combination with a plurality of resistance 40 varying devices having independent supports, and correspondingly disposed operating shafts, of means to coact with the supports of said devices for mechanically uniting and electrically connecting the latter,

each of said supports having edge portions extending in parallel relation to the respective operating shaft of its associated resistance control device, said means comprising parallel edge portions to coact with the aforementioned edge portions of said supports for maintaining coplanar relation of said operating shafts and said means being 50 further so formed as to provide for maintaining telescopic relation of said shafts to thereby provide for relative axial adjustment thereof.

14. In resistance control apparatus, the combination with a plurality of resistance 55 varying devices having independent substantially U-shaped metallic supports, of means to coact with the supports of said devices for mechanically uniting the latter, 60 each of said supports having edge portions extending in parallel relation to the operating shaft of its associated resistance control device, said means comprising parallel edge 65 portions to coact with the aforementioned edge portions of said supports for maintaining parallel relation of said axes, certain of said supports having means to provide for mounting upon a common base of all the devices so united.

15. In resistance control apparatus, the combination with a rheostat having associated supporting means, of an attachment for substantially augmenting the total ohmic 70 value of said rheostat comprising an auxiliary resistor device having terminal means including a rigidly secured terminal device having parts to cooperate directly with said rheostat supporting means to provide both mechanical support and terminal connection 75 of said auxiliary resistor device in circuit with said rheostat, said resistor device being of flexible construction to provide for accurate positioning thereof with respect to said supporting means and in radially spaced relation to said rheostat.

In witness whereof, I have hereunto subscribed my name.

HENRY J. WIEGAND.
